COIN TESTING DEVICE

Ernest O. Eason, Adams City, Colo.

Application July 31, 1936, Serial No. 93,643

15 Claims. (Cl. 194—101)

This invention relates to improvements in coin controlled devices and has reference more particularly to an improved coin testing mechanism for use with a coin controlled vending device.

5 In the dispensing of many kinds of merchandise, vending devices have been invented and used, which do not require an attendant, but which are controlled by a coin and operate to deliver a quantity of merchandise whose value 10 at the then market price equals the value of the coin.

It is found, by experience, that some people cannot resist the temptation to employ slugs of the shape and size of the coin or coins with which 15 the device has been designed to operate, and oftentimes these slugs are so expertly made that they will pass the ordinary tests to which such vending devices usually subject them. Such slugs are, of course, usually made of a base metal, 20 such as copper, but, on account of the seigniorage, silver slugs can also be substituted for the silver coins with profit.

It is obvious that automatic coin controlled dispensers cannot be successfully operated unless 25 some means is provided that will accept only regularly minted coins, and reject all slugs, regardless of the material of which they are made.

It is evident, however, that silver slugs of the 30 same shape, size, weight and density as regularly minted coins cannot be distinguished by any apparatus of practical construction. The slugs employed for the purpose of operating vending machines are, however, usually rather indifferently made, with the result that some of their physical 35 properties, such as their electrical conductivity, their elasticity or their magnetic properties differ from those of regularly minted coins.

The materials usually employed for slugs are 40 iron, copper, brass, zinc, tin, lead and aluminum. Iron, being magnetic, can be rejected by some magnetic means, and offers no difficult problem. Lead, tin, and zinc, differ quite widely from silver 45 in their elastic properties, and can be separated by a bouncing test. Copper metals which have been subjected, during manufacture, to high pressure, are the most difficult to detect, because such slugs have an elastic modulus so nearly the same as silver that they will frequently pass the elasticity test, for it is evident that such machines, 50 as are here under consideration, cannot be too closely adjusted. The Smithsonian tables give the hardness of pure silver and pure copper as 2.5—3 or equal one to the other. Silver coins contain ten per cent of copper and this alloy is 55 harder than pure copper, which increases the

rebound velocity. The electrical conductivity remains substantially the same as that of pure silver.

It has been found that silver, copper, bronze and brass are affected somewhat differently by 5 an alternating magnetic field. An alternating or variable magnetic flux produces a repulsive effect on all non-magnetic metals, and this varies very appreciably between different metals and alloys, and is substantially the same for copper or copper 10 alloys and for pure silver, or silver of such purity as is used in United States silver coins, and this property is taken advantage of in the present device to effect the desired selection.

The method of effecting a selection between 15 silver coins and slugs, which is employed in this invention consists in dropping the coins and slugs from a given height, onto an inclined surface of elastic material, such as steel, which surface is 20 preferably inclined with respect to the path followed by the coin in dropping. The coin, or slug, striking the elastic surface, or anvil, rebounds along a different path and at a velocity proportional to its elasticity. Silver coins, being 25 of a uniform density and elasticity, will follow a given path, while slugs of similar shape and size, but of less elasticity, will rebound at less velocity, and in this way, separation can be effected. Since 30 coinage silver is harder than copper, its rebound velocity will be greater and since the momentum varies with the square of the velocity, silver coins 35 will pass through a field that will inhibit the copper coins or slugs from passing.

After the coins have rebounded from the anvil, they are made to pass through an alternating 40 magnetic field, whose density is so regulated that it will permit a silver coin to pass and reach a position on an inclined support located beyond this field, but which will so retard copper coins 45 that they will not reach the support, and therefore fall into a reject chute. Slugs of magnetic material, such as iron, will be attracted and entirely stopped by the action of the magnet.

Copper has a slightly greater degree of conductivity than pure silver or coinage silver. 45 Bronze, brass, nickel and their various alloys have an elasticity closely comparable to coinage silver and considerably greater than pure silver, but their electrical conductivity is decidedly lower. When the coin to be tested is so located 50 as to act as a secondary for a primary coil, excited by an alternating electrical current, an induced current will be set up in the secondary or coin, the intensity of which will be directly proportional to the conductivity of the metal of 55

which the coin or slug is made, and in opposite or 180° phase with the primary which causes an alternating magnetic flux that is always in opposing relation to the primary flux.

5 The magnetic flux in the primary coil being in opposite phase to the magnetic flux in the secondary, (coin or slug) in effect repels the coin or slug proportionately to the intensity of the current generated in the coin, the strength or 10 intensity of the current being proportionate to the conductivity of the metal of which the coin is made.

Brass, bronze, nickel and certain similar alloys 15 having elasticity equal to or greater than silver, are rebounded through the path of magnetic flux at an equal or greater velocity than silver. The intensity of the current generated in these metals being less than in silver, there will be less counter 20 M. M. F. tending to prevent the slug from entering the field of magnetic flux in primary coil. This allows these metals to pass through and beyond the flux field of the coil. The coin or slug is supported on a plane inclined toward the source of impact, at an angle predetermined to allow 25 gravity to overcome counter M. M. F. set up in these metals, and will roll down the inclined plane into the reject chute.

Copper, hardened by compression as in metals, 30 has an elasticity slightly less but very closely approaching that of coinage silver. Therefore, the velocity from impact is nearly equal to silver. Since copper has a slightly greater conductivity than silver, it will generate a greater eddy current, and therefore a greater M. M. F., tending 35 to prevent the secondary or coin from entering the field of magnetic flux of the primary coil. By combining the effects of the reduced velocity of the coin from impact on the anvil with the greater M. M. F. generated in the coin, it is prevented 40 from passing the center of the field of magnetic flux in the primary coil and is repelled into the reject chute by its own M. M. F. combined with gravity.

By adjusting the strength of the alternating 45 current in the primary coil all other electrical characteristics in the apparatus will be correspondingly adjusted within certain limits. The counter M. M. F. tending to prevent the silver coin from entering the field of magnetic flux can be so adjusted as to barely permit the coin to 50 pass into and through the magnetic field. By permitting the coin to be rebounded from the inclined anvil and through the magnetic field and allowed to come to rest on a plane support located just beyond the field of magnetic flux and 55 inclined toward the flux field, the coin will roll by gravity toward the magnetic field.

The angle of the inclined support is adjusted 60 so that the counter M. M. F. repelling the coin is just great enough to prevent the force of gravity from causing the coin to roll back through the magnetic field into the reject chute located between the impact anvil and the primary coil. This arrangement of apparatus makes the return 65 of good coins to the purchaser of the vended commodity certain, in the event of the failure of the supply of current, and by mechanical arrangement of the electrical switches may be arranged to return the coin in event of depletion of vended 70 stock. This return action becomes automatic, since the coin will roll down the inclined support through the air gap arranged to concentrate the flux, in event there is no current flowing in the primary coil.

75 Aluminum has a degree of conductivity ap-

proaching closely to that of copper and silver, and, since its specific gravity is low and its elasticity, when compared to its weight, is greater than silver it becomes necessary in this device to provide a mechanical retard to the free gravitational action to reduce the velocity of aluminum slugs when rebounded from the elastic anvil. 5

Having thus briefly described the invention, the mechanism by which the method is carried out will now be described, and for this purpose, 10 reference will be had to the accompanying drawings, in which the essential elements thereof have been illustrated in their proper relation, and in which

Figure 1 is a side elevation, looking at the machine from the rear side thereof, parts being broken away to better disclose the construction; 15

Figure 6 is a section taken on line 6—6, Figure 1;

Figure 7 is a fragmentary section, similar to that shown in Figure 6, and shows the parts in a different position;

Figure 8 is a diagram, to scale, showing the relative location of the several parts and the path followed by a silver coin and by a slug; and

Figure 9 is a fragmentary section showing a slightly modified construction.

In the following description the slugs will also be referred to as coins, because the technical distinction is not material; the method of selection depending on the physical properties, and not on the impression placed thereon at the mint. 40

In the drawings, numeral 5 designates a metal plate which forms a base or support for the several parts of the mechanism. The base is provided with an opening 6 whose diameter is such that it will admit a silver dollar. Secured to the base, below opening 6, and to the left thereof, is a guide plate 7, having its edge 8 vertical and the edge 9 inclined.

A pendulum-like member 10 is mounted to swing about a pivot 11, and has a downwardly 50 extending narrow arm and a counterweight or head 12, that normally rests on the stop 13. The pivot 11 is so positioned that the distance between the inclined surface 9 and the opposed inclined surface 14 of the pendulum, at the height of the 55 pivot, is slightly greater than the diameter of a silver dollar.

The opening 6 is positioned with its center on the perpendicular bisector of a horizontal line joining the inclined guide surfaces, and passing 60 through the pivot. Located below the guide 7 and to the right of the inclined edge 9 extended, is an anvil 15 whose upper end is inclined downwardly toward the left, so as to form an angle of less than 90° with line a—b. The dotted line, 65 designated by reference characters c, d, e, f and g, indicates the path of the center point of a silver dollar in its passage through the device.

When a silver dollar is inserted through the opening 6, it drops, perpendicularly, until its center reaches point d when the left side thereof comes into contact with the inclined guide edge 9 after which it will slide along this edge with its center following line d—e. The pendulum 10 engages the right hand side of the dollar and pre- 75

vents it from bouncing away from the edge 9 with the result that after it leaves the guide edge it will travel in a substantially straight line until it strikes the anvil surface 16.

Upon striking the anvil surface the coin will rebound and its center will follow line *e-f* until it strikes the stop 17, whose edge is beveled as indicated at 18 in Figure 2. A movable support 19 holds the coin from falling downwardly along line *f-g* at this point.

A triangular member 20 separates the reject passage R from the passage A that leads to a coin box. As clearly shown in the drawings, the upper surface of the support 19 is inclined toward the reject opening R, and it is evident that the coin would roll downwardly and into the reject opening unless restrained by some means.

An alternating current electromagnet comprising two laminated pole pieces 21 and 22 and a coil 23 is attached to a plate 24 of brass or other non-magnetic material. The poles 21 and 22 are positioned as shown in Figure 8, from which it will be seen that the upper left hand corner of pole 21 extends up over the top of the support 19, and serves as a stop. There is no physical contact between the coin and the pole piece 21, but the magnetic flux that crosses to the plate 5, which is of magnetic material, sets up eddy currents in the coin, and the reaction tends to urge it toward the left, and prevents the coin from rolling along the inclined surface. It will hereafter appear that the magnet is energized when the coin is inserted through opening 6, and remains energized until the coin is deposited in the coin box, and therefore the coin must traverse the alternating magnetic flux in its rebound along path *e-f*.

When the coin cuts the magnetic flux, currents are set up which interact with the flux to produce a repulsive effect, whose intensity varies with the flux density and the latter must therefore be so proportioned that it will permit a silver coin, like those employed for money, to pass.

A copper coin, unless highly compressed, will not be able to pass through the magnetic field, and will fall into the reject opening R. Aluminum is so light that it will be greatly retarded by the action of the pendulum 10, and will not follow line *d-e*, but will drop almost vertically after it leaves the guide edge 9 and roll into the reject opening. Coins of lead or other non-elastic metal will not bounce to any appreciable extent, and will fall into the reject opening. Coins, or slugs, of iron have sufficient elasticity to carry them along path *e-f*, to the stop 17, but are so strongly attracted by the magnet that they are stopped thereby, and are retained by pole 22 of the magnet until the latter is de-energized, when they fall into the reject opening. The several steps in the method can be clearly seen from Figure 8.

In order to apply the method above described, to a practical purpose, a certain mechanism must be employed and this will now be described. The stop 17 is formed by the lower end of a steel bar, designated by the same reference numeral, and which is spaced from the vertical edge 8 of the guide 7 so as to form a space for the plunger 25.

A cover plate 26 rests on the bars 7 and 17, and on the anvil 15 and separator 20, and is also provided with spacers 27 and 28. The distance between the adjacent surfaces of the base 5 and the plates 24 and 26 is slightly greater than the thickness of a silver dollar.

The plunger bar 25 terminates at its lower end

in an inclined surface 29 and has a lateral extension 30 that covers the opening 6 when the bar is in its lowermost position, as shown in Figure 1, but which will be located wholly above this opening when the plunger bar is raised before the coin is inserted. A spring 31 tends to move bar 30 downwardly, while a dash pot 32 serves to retard its downward movement while permitting free upward movement.

Plate 5 has a slot 33 and the plunger bar has a handle 34 that projects through this slot so that the bar can be raised from the outside.

Attached at its upper end to the bar 25 is a narrow bar 35 that is provided on its right-hand edge with a cam notch 36. Bar 35 is on the outside of plate 26, and the latter carries a lever arm 37 which is mounted to turn about a pivot 38. Lever 37 has a short arm 39 and a long arm 40. A tension spring 41 has one end attached to the long arm, and the other anchored to the plate 26, and serves to urge the end of the arm 39 against the edge of the bar 35, and when the latter is moved upwardly from the position shown in Figure 1, it will rotate the lever 37 clock-wise about its pivot.

A shaft 42 extends between the supports 43 and 44, and carries a mercury switch 45 that is supported by a suitable holder 46. A lever arm 47 extends from the shaft toward the plate 26, and controls the position of the switch. A rod 48 has its upper end connected with the lever 40 and its lower end connected with arm 47, and when lever 37 is turned clockwise about its pivot, the mercury switch will be turned counter-clockwise (Figure 3) until the mercury connects the two terminals therein.

It will be seen from this that as soon as the plunger bar is raised, for the purpose of uncovering the opening 6, the circuit from the alternating current source 49 is closed to the magnet 50 and remains closed until the plunger returns to the position shown in Figure 1.

The support 19 is formed integral with arm 50, the connection being indicated by reference numeral 51. A link 52 is pivoted to shaft 42, and has its free end pivotally connected with the arm 50 at 53. A tension spring 54 has one end connected with the link 52 near the shaft 42, and the other end connected to arm 50 at 55. It will be observed that spring 54 produces a force having two components, one tending to move the arm 50 upwardly, and the other tending to rotate it counter-clockwise about pivot 53. A plate 56 is attached to the arm 50, and extends outwardly therefrom.

The magnetic circuit of the magnet is formed in part by an armature 57 that is hinged to move about the pivot 58 at the outer end of the pole piece 22. The pole pieces 21 and 22 and the armature 57 are laminated and held between side pieces of non-magnetic material, one of which has been indicated by numeral 59, and this projects across the arm 50, in the manner shown most clearly in Figure 1.

Plate 26 carries a curved arm 60 whose end 65 rests upon the plate 24, and serves as a stop for the support 19 when it is in the position shown in Figures 1, 4 and 6.

Let us now assume that the parts are in the position shown in Figures 1, 3, 4 and 6, and that the handle 34 is grasped and moved upwardly. By the initial movement of the plunger bar 25, the lever 37 will be rocked, and the circuit to the magnet will be closed by the mercury switch. As soon as the magnet is energized, the hinged

armature 57 is pulled towards the pole piece 21 and part 59 engages plate 56 and moves the arm 50 and support 19 towards base 5 until the support is free to move upwardly into the space between base 5 and plate 24, when the spring 54 will act to move it into the position shown in Figure 7.

When the opening 6 has been uncovered, a silver dollar is inserted and permitted to drop, and soon thereafter it is in position on the support 19 as shown in Figure 8.

As soon as the handle 34 is released, spring 31 starts returning the plunger bar, but this is retarded by the dash pot. The retardation does not have to be great as the time it takes the plunger bar to return does not affect the operation.

When the lower end 29 of the plunger 25 engages the coin, the support 19 will begin to move downwardly, and soon thereafter switch 45 will be opened and the magnet de-energized. As the support reaches the lower edge of plate 24, it will be pulled outwardly and against the stop 60, by the spring 54, and the coin will drop into the coin box, and soon thereafter the parts will all be in the position shown in Figure 1.

If the coin is of such material that it will not reach a position on the support, the parts will return to the position shown in Figure 1, with the exception of the support 19 which will remain in the position shown in Figure 7. If a magnetic slug is used, it will be retained by the magnet pole 22 until the latter is de-energized, when it will drop into the reject opening.

Attention is called to the fact that the apparatus that has been illustrated and described has been greatly altered from the form in which it is embodied for practical operation so that the important features thereof could be more easily illustrated and explained, and it is not intended that the device, in the exact form illustrated is suitable for a vending machine. The parts illustrated do, however, constitute an operative testing device.

In the actual device the support 19 is returned to its operative position after each operation so that it will return any coins to the reject opening if inserted when the current is off. By constructing the stop 69 as shown in Figure 9, the stop 19 will be automatically returned to operative position by the action of the spring 54, and when so constructed the hinged armature 57 can be formed integral with the pole pieces 21 and 22.

One reason for inclining the upper or supporting edge of member 19 is to cause the coin to roll into the reject opening if the current is off at the time the coin is deposited, and another object is to effect a return to the reject opening of slugs that pass through the magnetic field. Another important object is to allow certain adjustments to be made to compensate for variations in voltage.

It is evident that the alternating magnetic field cannot exceed that which will permit a silver coin to pass through it and onto the support 19. After the silver coin has been deposited on the support, it must be prevented from rolling into the reject opening. Since the support is inclined, the effect of gravity will be resolved into two components, one of which is vertical and the other parallel with the inclined surface of the support. By means of a special tool, the inclination of the support can be adjusted to conform to the strength of the magnetic field.

Although the operation has been explained in

connection with a silver dollar, the apparatus will function equally well with a fifty cent piece and with a quarter.

Having described the invention, what is claimed as new is:

1. An apparatus for separating round silver coins from coins of other metals, but of the same size, and shape, comprising an anvil of elastic metal, having an impact surface at its upper end, means for directing a coin edgewise onto the impact surface, along a path inclined thereto, whereby it will rebound along a path and at a velocity corresponding to its modulus of elasticity, a support spaced from the anvil in position to receive a silver coin after its rebound, the support being inclined towards the anvil there being an open space between the anvil and the support, forming a reject opening, means interposed between the anvil and the support for producing an alternating magnetic flux across the rebound path, the strength of the flux being adjusted to the maximum for the passage of silver coins therethrough, the degree of the inclination of the inclined support being so proportioned to the flux density that the silver coin will not roll into the reject opening, and means for removing the support after a predetermined time interval whereby a coin resting thereon will drop by the action of gravity.

2. An apparatus for separating round silver coins from coins of other metal of the same size, comprising, in combination, an anvil of elastic material having a horizontally inclined impact surface at its upper end, means for directing a freely falling coin edgewise onto the impact surface, whereby the coin will rebound along a path, and at a velocity corresponding to its modulus of elasticity, a stop forming the end of the rebound path, a movable support adjacent the stop, inclined towards the anvil, in position to receive and support the coin after its rebound, there being a reject opening between the anvil and the support, means for subjecting the rebound path, at a point between the anvil and the support, to an alternating magnetic flux of a density that will barely permit a silver coin to pass, the degree of inclination of the support being so proportioned to the flux density that the silver coin will not roll past the magnet and into the reject opening, and means for removing the support and directing the coin into a coin compartment.

3. An apparatus for separating round silver coins from coins of other metal of the same size and shape, comprising in combination, an anvil of elastic material having a horizontally inclined impact surface at its upper end, means comprising a guide member having an edge slightly inclined to the vertical for guiding a coin, means for holding a coin in contact with the guide edge while falling, means for directing a freely falling coin edgewise onto the impact surface of the anvil, whereby the coin will rebound along a path, and at a velocity corresponding to its modulus of elasticity, a stop forming the end of the rebound path, a movable support adjacent the stop, inclined towards the anvil, in position to receive and support the coin after its rebound, means for subjecting the rebound path, at a point between the anvil and the support, to an alternating magnetic flux of a density that will barely permit a silver coin to pass, there being a reject opening between the anvil and the support, and means for removing the support and directing the coin into a coin compartment.

4. An apparatus for separating round silver

coins from coins of other metal of the same size and shape, comprising, in combination, an anvil of elastic material having a horizontally inclined impact surface at its upper end, means for directing a freely falling coin edgewise onto the impact surface, whereby the coin will rebound along a path, and at a velocity corresponding to its modulus of elasticity, a stop forming the end of the rebound path, a movable support adjacent to the stop, inclined towards the anvil, in position to receive and support the coin after its rebound, means comprising an alternating current electromagnet, positioned between the anvil and the support, for subjecting the rebound path to an alternating magnetic flux of such density that it will barely permit a silver coin to pass, there being a reject opening between the anvil and the support, means for removing the support after the coin has reached the same, and means for de-energizing the electromagnet as the support is being removed.

5. An apparatus for separating round silver coins from coins of other metal of the same size and shape, comprising in combination, an anvil of elastic material having a horizontally inclined impact surface at its upper end, means comprising a member having an edge slightly inclined to the vertical for guiding a coin, means for holding a coin in contact with the guide edge while falling, said guide member and coin holding means serving also as means for directing a freely falling coin edgewise onto the impact surface of the anvil, whereby the coin will rebound along a path, and at a velocity corresponding to its modulus of elasticity, a stop forming the end of the rebound path, a movable support adjacent to the stop, in position to receive and support the coin after its rebound, the upper surface of the support being downwardly inclined in the direction of the anvil, there being a reject opening between the support and the anvil, means for subjecting the rebound path, at a point between the anvil and the support, to an alternating magnetic flux of a density that will barely permit a silver coin to pass, and means for removing the support and directing the coin into a coin compartment.

6. An apparatus for separating round silver coins from coins of other metal of the same size and shape, comprising in combination, an anvil of elastic material having a horizontally inclined impact surface at its upper end, means for directing a freely falling coin edgewise onto the impact surface, whereby the coin will rebound along a path, and at a velocity corresponding to its modulus of elasticity, a stop forming the end of the rebound path, a movable support adjacent to the stop, inclined towards the anvil, in position to receive and support the coin after its rebound, means for subjecting the rebound path, at a point between the anvil and the support, to an alternating magnetic flux of a density that will barely permit a silver coin to pass, there being a reject opening between the support and the anvil, means for removing the support and directing the coin into a coin compartment, means for latching the support in inoperative position, and means for unlatching the support and returning it to operative position.

7. An apparatus for separating round silver coins from coins of other metals, but of the same size, comprising an anvil of elastic metal, having an impact surface at its upper end, means for directing a coin edgewise onto the impact surface, along a path inclined thereto, whereby it will

rebound along a path and at a velocity corresponding to its modulus of elasticity, a stop forming the end of the rebound path, a movable support spaced from the anvil in position to receive a silver coin after its rebound, the upper surface of the support being downwardly inclined in the direction of the anvil to produce a tendency for the coin to roll towards the anvil, there being an open space between the anvil and the support, forming a reject opening, means for moving the support to inoperative position to release the coin, and means interposed between the reject opening and the support for producing an alternating magnetic flux across the rebound path, the strength of the flux being adjusted to the maximum for the passage of the rebounding silver coins therethrough.

8. A coin selecting and testing device, having a base comprising a plate normally occupying a vertical position, an anvil secured to the plate and provided with an impact surface at its top, the plate having a hole at some distance above the anvil through which a coin can be inserted, means for directing the coin so that it will strike the impact surface with its edge, the surface at the point of impact being inclined with respect to the path of the coin, whereby it will rebound along a path angularly related to the incidence path, a stop at the end of the rebound path, a movable support located below the stop in position to receive the coin at the end of its travel, the upper surface of the support being inclined downwardly toward the anvil, there being a reject opening between the support and the anvil, means comprising an electromagnet located between the anvil and the stop for subjecting the rebound path to an alternating magnetic flux, whereby a force is produced tending to resist the movement of a coin of conductive material therethrough, the flux strength being adjusted to barely permit a rebounding silver coin to pass, means for removing the support to permit the coin to drop, and means for stopping the production of magnetic flux when the coin is released by the support.

9. A coin selecting and testing device, having a base comprising a plate normally occupying a vertical position, an anvil secured to the plate and provided with an upper impact surface, the plate having a hole at some distance above the anvil through which a coin can be inserted, means for directing the coin in its passage to the anvil so that it will strike the impact surface with its edge, the surface at the point of impact being inclined with respect to the path of the coin, whereby it will rebound along a path angularly related to the incidence path, a stop at the end of the rebound path, a movable support located below the stop in position to receive the coin at the end of its travel, the upper surface of the support being inclined downwardly toward the anvil, there being a reject opening between the support and the anvil, means comprising an electromagnet energized from a source of alternating current, located between the anvil and the stop for subjecting the rebound path to an alternating magnet flux whose density is adjusted to barely permit a rebounding silver coin to pass, whereby a force is produced tending to resist the movement of a coin of conductive material in its rebound passage from the anvil towards the stop and for resisting movement of the coin from the support towards the reject opening, means for removing the support to permit the coin to drop,

and means for de-energizing the electromagnet when the coin is released.

10. An apparatus for use in separating silver coins from coins of similar size and shape, but 5 made from metals having physical properties different from silver, comprising in combination, a base provided with a substantially vertical chute of a size that will permit the largest coins employed to fall freely, a guide located in the chute 10 and provided with a guide wall, means for urging a falling coin towards the guide wall and for subjecting it to a retarding force, comprising a pendulum, pivoted near its top, the edge of the pendulum facing the guide wall being normally 15 inclined towards the guide wall in a downward direction, the pendulum being counter-balanced to normally maintain this position, and an anvil located in the path of the falling coin and provided with an impact surface inclined with respect to the 20 path of the coin whereby the coin, after impinging thereon, will rebound along an upwardly and outwardly inclined path.

11. An apparatus for use in separating silver coins from coins of similar size and shape, but 25 made from metals having physical properties different from silver, comprising in combination, a base provided with a substantially vertical chute of a size that will permit the largest coins employed to fall freely, a guide located in the chute 30 and provided with a guide wall, means for urging the coin toward the guide wall, and for subjecting the coin to a retarding force, an anvil located in the path of the falling coin and provided with an impact surface inclined with respect to the 35 path of the coin whereby the coin, after impinging thereon, will rebound along an upwardly and outwardly inclined path, means for subjecting the rebound path to an alternating magnetic flux for producing a retarding influence on the 40 coin, a stop at the end of the rebound path, a movable support located adjacent the stop to receive and support the coin, there being a reject opening between the support and the anvil, the upper surface of the support inclining downwardly towards the reject opening to provide a 45 gravitational component tending to roll a circular coin towards the reject opening, the strength of the magnetic flux being so adjusted that it will barely permit a rebounding silver coin to pass and the degree of inclination of the supporting 50 surface being so proportioned to the strength of the flux that the circular silver coin will be held from rolling towards the reject opening, and means for removing the support to permit the coin to drop.

12. An apparatus for use in separating silver coins from coins of similar size and shape, but made from metals having physical properties different from silver, comprising in combination, a 60 base provided with a substantially vertical chute of a size that will permit the largest coins employed to fall freely, a guide located in the chute and provided with a guide wall, means for urging the coin toward the guide wall, and for subjecting the coin to a retarding force, an anvil located in the path of the falling coin and provided with an impact surface inclined with respect to the path of the coin whereby the coin, after impinging thereon, will rebound along an upwardly and out-

wardly inclined path, means for subjecting the rebound path to an alternating magnetic flux of a density that will barely permit a silver coin to pass, for producing a retarding influence on the coin, a stop at the end of the rebound path, a 5 movable support located adjacent the stop to receive and support the coin, the upper surface of the support being downwardly inclined in the direction of the anvil, there being a reject opening between the support and the anvil, means comprising a plunger for engaging the top of the coin and forcing it downwardly against the support, and means responsive to the pressure of the coin on the supporting surface for moving the support to inoperative position.

13. The method of separating metal coins of the same size and shape, having different physical properties, comprising, dropping them edgewise onto an elastic surface inclined with respect to the path of the falling coins, whereby they will 20 rebound along an upwardly inclined path, subjecting the rebound path to a fluctuating magnetic flux, for exerting a retarding action on the rebounding coins, supporting the coins that have passed through the magnetic flux within the influence of the magnetic field, subjecting the coins while thus supported to a component of the force of gravity tending to return it through the magnetic field to a reject opening, and then removing the support.

14. The method of separating silver coins from coins of other metals, of the same size and shape and having different moduli of elasticity which consists in dropping the coins separately from the same height and on edge onto an elastic metal 30 surface, inclined with respect to the path of the coins, whereby they will rebound along an upwardly inclined path at velocities corresponding to their elasticities, subjecting the rebound path to a fluctuating magnetic flux of a density slightly below the maximum for passing silver coins, supporting the silver coins that pass the flux within the influence of the magnetic flux, on a surface inclined toward the elastic surface whereby there will be a component of the force of gravity tending to return the coins through the magnetic field to a reject opening, and then removing the support and permitting the coin to drop.

15. In a coin testing device having an anvil for 50 effecting a rebound resiliency test, means for directing coins of different sizes onto the anvil so that all will travel in parallel incidence paths regardless of size, said means comprising a guide plate having one edge downwardly ranging to 55 form a guide, a pendulum mounted for free swinging movement about a pivot and having a downwardly extending arm having a guide edge that faces the guide edge of the guide plate, the two guide edges being inclined towards each 60 other in a downward direction whereby a downwardly tapered passage is formed, the width of the passage at the level of the pivot being sufficient to receive the largest coin used and the normal width of the passage at its lower end being less 65 than the diameter of the smallest coin used, the pendulum being swingable to permit the largest as well as the smallest coins to pass.
